UNITED STATES PATENT OFFICE.

WILLIAM MAXWELL REED, OF LOUISVILLE, KENTUCKY, ASSIGNOR TO LOUISVILLE AUTO PAINTING AND TRIMMING COMPANY, OF LOUISVILLE, KENTUCKY, A CORPORATION OF KENTUCKY.

AIR-CLEANSING DEVICE AND VENTILATOR.

1,416,381.

Specification of Letters Patent. Patented May 16, 1922.

Application filed January 14, 1921. Serial No. 437,182.

To all whom it may concern:

Be it known that I, WILLIAM MAXWELL REED, a citizen of the United States, residing at Louisville, State of Kentucky, have invented certain new and useful Improvements 5 in Air-Cleansing Devices and Ventilators; and I do hereby declare the following to be a full, clear, and exact description of the invention, such as will enable others skilled 10 in the art to which it appertains to make and use the same.

This invention relates to an air cleansing device and ventilator, with particular reference to an apparatus of this character 15 adapted to be used in connection with drying rooms or chambers wherein it is desired to ventilate the same and maintain a circulation of air therethrough, entirely free from dust, dirt or other foreign matter or impuri- 20 ties.

Primarily, the device is adapted to be installed in a drying or finishing room commonly employed in the drying of painted or varnished vehicle bodies, where it has been 25 found necessary to maintain a circulation of air through said rooms or chambers and at the same time exclude all dirt, dust and the like, the presence of which would obviously injure or impair the appearance of the 30 finished article.

In drying rooms of this character, if the air therein is not constantly changed, the same, within a short time, will become so damp and humid that it will not take up 35 any more moisture, and, consequently, the drying process will come to a standstill, the articles therein becoming more or less sticky, resulting in a loss of the gloss and luster required of the finished article. Furthermore, 40 the air will become so saturated with turpentine as to make it practically impossible for the employees to work in the room, and in some instances the turpentine and similar vapors will have an injurious effect on the 45 paint and varnish on the articles being put through the drying process.

The principal object of this invention is to provide a device of the character indicated that will overcome the various disadvantages 50 above noted, whereby the air is drawn into and forced through the drying room, thus maintaining a circulation of air at all times, means being provided for previously extracting all dust and dirt from the air just prior 55 to its entrance into the room.

Another object of the invention is the provision of an arrangement of this description which will be simple in operation and construction, cheap to manufacture, and one that by reason of its unitary construction 60 can be adapted to and used in connection with the ventilating of various plants, such as dynamo rooms, public halls, and other places where a continuous supply of clean 65 fresh air is desired.

As hereinbefore stated, it is not only necessary that the air in the drying room be renewed and a circulation maintained, but it should also be cleansed of all foreign particles, such as dirt and the like, and the invention further contemplates a means whereby this may be accomplished in a simple manner, as the air is being drawn into the room, the details of which arrangement will 70 be hereinafter more fully described.

Generally stated, the invention comprises an air cleaning and suction device, preferably positioned at an opening in one wall of a drying room, or similar chamber, whereby air is drawn into the room and caused to 80 circulate therethrough, passing out of another opening arranged for the purpose, the room or chamber adapted to be made substantially airtight with the exception of the air inlet and outlet openings.

The air cleaning and suction device per se comprises, preferably, a casing of square funnel shape, having its big end closely positioned in the opening formed in one of the walls of the room, and its small end supported upon uprights or standards, said big end being inclosed by a frame supporting a series of narrow trays positioned between a pair of spaced wire mesh screens through which the air is drawn by a suction fan 90 mounted in the small or reduced end of the device. In the space between the screens and trays is a filling of steel wool or similar material previously saturated with oil, which, having an attraction for dirt and the like, extracts all dust and foreign particles 95 from the air passing therethrough into the drying room, the trays merely acting as drip pans to catch the excess oil that percolates down through the saturated material.

The preferred embodiment of the invention is illustrated in the accompanying drawings, in which—

Fig. 1 is a diagrammatic, fragmentary view, showing the manner of positioning the 110

device with respect to the drying chamber.

Fig. 2 is a rear view of said device, showing the means of supporting the inner end thereof.

5 Fig. 3 is an enlarged perspective view illustrating the air cleansing arrangement, and

Fig. 4 is a detailed, sectional view of the air cleansing screen.

10 Referring to the drawings in detail, the air cleansing and ventilating device comprises a square, funnel-shaped casing 1, adapted to be positioned in an inlet opening 2 provided in the wall of a drying room or 15 chamber 3, said chamber being also constructed with an air outlet opening 4, placed at any convenient location as may be found desirable for the most successful and efficient 20 operation of the ventilating arrangement.

20 Upon referring to Fig. 1 of the drawings, it will be noted that the large end of the funnel-shaped casing is adjusted to and supported within the opening 2 of the chamber 3, and the small end thereof, which 25 projects inwardly of the chamber, is supported upon standards 5, provided with a supporting base 6 adapted to rest upon the floor of said chamber. This is the preferred form of support, but obviously any other 30 means of bracing or supporting this inner end may be employed, to suit the various conditions and locations where it might be found necessary to locate the device with respect to the drying chamber.

35 The air cleansing and ventilating device per se, it will be noted upon referring to the enlarged detailed views in Figs. 3 and 4, is, as hereinbefore stated, of square funnel shape, the hollow casing 1 preferably of

40 sheet metal having an enlarged square end and a reduced end portion terminating in an annular extension 7 in which is adapted to be mounted a fan 8, preferably of the electric type, and suitably connected with 45 the necessary source of power for operating said fan, which fan provides the means of constantly furnishing a fresh supply of air to the drying chamber and causing the continuous circulation thereof through the dry- 50 ing chamber.

In order to extract all dirt and other foreign matter from the air before entering the drying room and to insure the entrance of only clean air thereto, the enlarged or 55 outer end of the casing 1 is supplied with a frame 9 provided on its opposite side faces with a pair of spaced wire mesh screens 10 and 11, the frame 9 being of sufficient depth to permit the desired spacing of the screens 60 10 and 11. Within the inclosure formed by the frame 9 and screens 10 and 11 is confined a filling or air filtering medium of steel wool or similar material 12, which has previously been saturated with oil or the like, and 65 through which material the air is drawn by

the fan 8 during the operation of the device, the screens 10 and 11 merely forming a means of holding or retaining the air filtering material 12 in position.

By reason of the fact that oil has a great 70 affinity for dirt and other extraneous substances, the saturation of the air filtering material with oil, and used in the particular arrangement hereinbefore described, provides a very simple and efficient means of 75 cleansing the air as it is drawn through the casing 1 and forced into the drying room or chamber by the fan provided for the purpose. In order to prevent the leakage of oil, which would obviously percolate down 80 through the porous filtering material, there is provided a series of transversely arranged pans or trays 13, which pans are supported within the frame 9 and also inclosed between the screens 10 and 11, as clearly shown 85 in Figs. 3 and 4. These trays will also prevent the settling or packing down of the filtering material as they form substantially a multiplicity of small compartments within the screens and frame. 90

In order to renew the filtering material when desired, and also replenish the supply of oil when necessary, the outside screen 11 is detachably secured to the frame 9 by a removable frame 14, as clearly shown in 95 Fig. 4. This outside screen 11 is also made detachable for the purpose of obtaining access to the pans or trays 13 and permitting the removing therefrom, when necessary, the accumulated oil at predetermined periods, 100 which oil is obviously saturated with dirt and other substances extracted from the air during its passage through the cleansing medium.

Although the invention has been illustrated and described with particular reference to drying rooms, chambers and the like, the same is not to be so limited, as obviously the arrangement and particular apparatus is equally well adapted for the ventilation 110 of various plants, dynamo rooms, public halls, and similar places where a continuous circulation and supply of clean, fresh air is desired.

What I claim is:

1. A device of the character described comprising a frame open at the front and rear, a plurality of horizontally disposed partitions extending transversely of the frame, a screen secured over each open face 120 of said frame, and a filling of air-filtering material confined within the frame upon said partitions and between said screens.

2. In an air ventilating and circulating device, adapted for use in connection with 125 drying rooms, chambers and the like, the combination with a fan, of a tubular casing adapted to be positioned in an opening in said room or chamber, a frame having transverse partitions positioned within the 130

casing, a screen secured to each side face of said frame, and a filling of air filtering material confined within the frame upon said partitions and between said screens.

5 3. In an air ventilating and circulating device, adapted for use in connection with drying rooms, chambers and the like, the combination with a fan, of a tubular casing adapted to be positioned in an opening in 10 said room or chamber, a frame positioned within said casing, a screen secured to each side face of said frame, and a series of pans and a filling of air filtering material confined within the frame and between said 15 screens.

4. In an air filtering or circulating device, the combination with a drying room, chamber or the like, of a funnel shaped tubular casing adapted to have its large end positioned in an opening in the wall of said room or chamber, means for supporting its 20 opposite end, a frame positioned in said large end of the funnel shaped casing, a screen secured to each side face of said frame, a series of pans and a filling of oil 25 saturated filtering material confined within the frame and between said screens, and a fan mounted in the small end of the funnel shaped casing for drawing the air there- 30 through and through the filtering material and forcing the same through and out of the drying room or chamber.

5. A ventilator comprising a casing open

at both ends, a fan disposed within one end of the casing, a frame secured to the opposite end of the casing, a plurality of horizontally arranged pans supported in the frame, sheets of absorbent material saturated with liquid supported in the pans, the latter serving to catch any liquid that may flow 40 from the absorbent sheets, and reticulated sheets secured to the opposite face of the frame to hold the absorbent sheets in place and to filter the air passing therethrough.

6. A ventilator comprising a casing open 45 at both ends, a frame mounted in one end of the casing, a plurality of horizontally disposed pans supported in the frame, sheets of absorbent material saturated with liquid supported in the pans, the latter serving to 50 catch any liquid that may flow from the absorbent sheets, and reticulated sheets secured to the opposite faces of the frame to hold the absorbent sheets in place and to filter the air passing therethrough.

7. A device of the character described comprising a frame, a plurality of horizontally disposed troughs supported in the frame, one above the other, wads of absorbent material supported by the troughs and 60 extending from one end of the latter to the other and also reaching from one trough to the other, and reticulated sheets removably secured to the opposite faces of the frame.

In testimony whereof I affix my signature. 65
WILLIAM MAXWELL REED.
